FIGURE 5

FIGURE 1 is a front and side perspective view of a magnetic tape recording and reproducing machine, showing our new design;

FIGURE 2 is a front elevational view, the back being conventionally plain;

FIGURE 3 is a right side elevational view;

FIGURE 4 is a top plan view, the bottom being conventionally plain; and

FIGURE 5 is a front and left side perspective view with the cover mounted.

We claim:

The ornamental design for a magnetic tape recording and reproducing machine, substantially as shown and described.
